PISTON EXPANDER

Walter J. Six, Indianapolis, Ind.

Application October 10, 1932, Serial No. 637,032

14 Claims. (Cl. 309—12)

This invention relates to expanding means for skirts of pistons adapted for use in engines, such as internal combustion engines, compression engines, steam engines and the like.

5 It is usual to provide such pistons with a head and a skirt which is partially or wholly separated from the head by a circumferential opening or openings. The lands between the ring grooves on the head are usually made slightly 10 smaller in diameter than the diameter of the skirt which is formed initially to closely fit the interior of the cylinder. The skirt, particularly when formed of aluminum or similar metal, is usually slotted longitudinally to permit the skirt 15 to expand and contract so that it will closely follow the cylinder wall. However, due to wear of the cylinder and the piston this closeness of fit between the skirt and the cylinder wall is soon destroyed with the attendant results of "piston 20 slap", undue leakage of the oil past the piston rings, and decreased efficiency of the engine. In order to overcome these defects without reboring the cylinders or replacing the pistons, it has been heretofore suggested that spring means 25 of some sort within the skirt be provided to expand the skirt.

The principal object of my invention is to provide an improved and simple expander which exerts an expansive action substantially about 30 the entire skirt while permitting the skirt to contract when necessary in operation, and thereby attain a more perfect fit between the worn skirt and the cylinder wall than has been possible heretofore.

35 The invention resides in a compressible spring expander adapted to be compressed within a worn piston to exert outward pressure against the skirt. More particularly, it relates to expanders of simple U-shape or cup-like form having a plurality of downwardly extending fingers which may form in effect a split wall adapted to engage and bear against the inner surface of the piston skirt over a substantial area to force it radially outward to conform to a worn or out-of-round cylinder. 40 For this purpose, a pair of oppositely disposed expanding fingers or wall sections bear against the slotted portion of the skirt and that portion opposite thereto, while another pair of fingers or wall sections may engage and press outwardly 45 against the opposed boss portions, to expand the circumferential length of the skirt.

The full nature of the invention will be more clearly understood from the accompanying drawing and the following description and claims:

50 Fig. 1 is a central vertical section through a

piston with the expander mounted therein. Fig. 2 is a section taken on the line 2—2 of Fig. 1. Fig. 3 is a plan view of the under side of the piston showing the expander therein. Fig. 4 is a perspective view of the expander removed from the 5 piston. Fig. 5 is the same as Fig. 4 showing a modified form of the expander. Fig. 6 is the same as Fig. 4, showing a second modified form.

In the drawing there is shown a piston of the usual type having a head 10, piston ring grooves 10 11, a peripheral slot 12 partially separating the head from the skirt 13, and inwardly extending projections in the form of piston pin bosses 14.

Said skirt is provided with a substantially longitudinal slot extending from the lower end to the 15 peripheral slot 12 on one side thereof intermediate the bosses, to permit of expansion and contraction to conform to the cylinder in which it operates.

For yieldingly expanding said skirt and imparting thereto a radial outward force under spring tension, there is provided an expander spring as illustrated in Fig. 4. Said spring is substantially U-shaped or "cup-like", being adapted to be forced in inverted position upwardly within the 25 piston skirt toward the head so that the downwardly extending expanding fingers or split wall sections bear against the inner surface or side walls of the split skirt of the piston.

To permit of the flexing of the expander under 30 pressure, it may be described as having a bight portion 16 adapted to lie adjacent the piston head. Extending downwardly from said bight portion, there are a pair of wall sections or resilient fingers 17 curved to conform with the curvature 35 of the piston skirt and adapted to be forced inwardly against the inherent spring tension therein when mounted within the skirt so as to normally exert an outward pressure thereon. Intermediate said fingers 17, there are oppositely 40 disposed wall sections or ears 18, which are so arranged as to engage the bosses 14 to normally exert an outward pressure against said bosses and the corresponding side of the skirt.

Said ears may terminate above the bosses so 45 as to interlock therewith as illustrated in Figs. 1 to 4, inclusive, or may extend downwardly about said bosses to embrace the same as shown in the modified form illustrated in Fig. 5, wherein the head 116 is provided with wall sections 117 to 50 engage that portion of the skirt intermediate the bosses while sections 118, provided with apertures 119, embrace and extend below the boss portions so as to bear thereagainst.

While the expander is herein shown specifically 55

as embodying oppositely disposed fingers and intermediate oppositely disposed ears, it may embody suitable expansion folds 220 separating the corresponding wall sections thereof as illustrated 5 in the modified form shown in Fig. 6.

From the foregoing, it will be observed that wherein a piston having a split skirt is caused to operate in an enlarged cylinder or an out-of-round cylinder, or wherein said piston has lost 10 its normal inherent expanding force, the installation of said expander therein will cause the skirt to spread so as to accommodate it to the cylinder in which it operates, while permitting of contraction owing to the longitudinal slot 15 therein and the yielding character of the expander.

It will also be noted that by reason of the cup shaped formation of the expander, it may be readily inserted in the piston and driven home 20 therein without the requirement of unusual tools.

The invention claimed is:

1. In combination with a piston having piston pin boss portions, and a skirt having a substantially longitudinal slot, of a compressible expander sprung into position within said skirt, the said expander being substantially U-shaped with the bight portion thereof lying adjacent the head of the piston and the freely extending finger portions bearing against the inner surface 30 of the skirt under spring tension so as to normally exert an outward pressure thereon, and oppositely disposed intermediate ears extending from the bight portion of said expander in engagement with said boss portions for exerting an 35 outward pressure thereagainst.

2. In combination with a piston having a head, piston pin boss portions, and a skirt having a substantially longitudinal slot intermediate said boss portions, of a compressible cup-like expander sprung into position within said skirt in inverted position with the bight portion thereof lying adjacent the head of the piston, oppositely-disposed depending wall portions of curved cross section conforming substantially to the curvature 45 of the piston skirt extending downwardly from the bight portion into engagement with the portions of the skirt intermediate the boss portions, one of said depending wall portions bearing against said skirt on each side of said slot, and 50 intermediate wall portions extending downwardly from the bight portion into engagement with the boss portions for locking the expander in place and exerting an outward pressure against the boss portions of the skirt.

55 3. The combination with a piston having a head, piston pin boss portions, and a skirt having a substantially longitudinal slot intermediate said boss portions, of a compressible cup-like expander sprung within said skirt in inverted 60 position with the bight portion thereof lying adjacent the head of the piston, oppositely-disposed depending wall portions extending downwardly from the bight portion into sliding frictional engagement with the skirt intermediate 65 the boss portions, one of said depending wall portions bearing against said skirt on each side of said slot, and intermediate members extending downwardly from the bight portion over said boss portions for preventing escape of the expander from the piston when in operation.

70 4. The combination with a piston having a split skirt and oppositely disposed crank pin bosses, of a spring piston expander located within the piston skirt and presenting line contacts 75 with the skirt to each side of the split and in

substantial parallelism therewith, and likewise bearing directly against each boss above its center line only and at that side thereof nearest the split.

5 5. The combination of a piston having a head, a slotted piston skirt, and piston pin bosses; and a piston skirt expander, said expander comprising oppositely disposed spring arms, said arms extending at an angle to the axis of said piston and converging toward said piston head, and means intermediate the upper portions of said spring arms encircling said piston pin bosses.

10 6. An expander for pistons comprising a U-shaped plate member formed from a steel stamping the sides of which comprise spring arms, and a perforated lobe projecting from said U-shaped member between said arms, said lobe lying in a plane parallel to a medial plane intersecting said arms.

15 7. An expander for pistons comprising a U-shaped plate member the sides of which comprise spring arms, and a pair of spaced perforated lobes projecting from said U-shaped member between said arms, said lobes being disposed in opposition and lying in planes parallel to a medial plane intersecting said arms.

20 8. An expander for pistons comprising a spring steel stamping having oppositely disposed plate-like wings having spaced ends adapted to form spring arms and oppositely disposed lobes intermediate the wings and the common axis of said lobes being at right angles thereto.

25 9. An expander for pistons comprising a U-shaped plate member the sides of which comprise spring arms, the free ends of said arms being arcuate in a transverse plane, and a pair of spaced perforated lobes projecting from said U-shaped member between said arms, said lobes being disposed in opposition and lying in planes parallel to a medial plane intersecting said arms.

30 10. An expander for pistons comprising oppositely disposed plate-like wings adapted to form spring arms having spaced ends and oppositely disposed lobes intermediate the wings and connecting necks between the lobes and the wings.

35 11. A piston skirt expander comprising a resilient body constructed to be positioned in a piston crosswise of a piston pin, said body having end portions arranged for engagement with opposite sides of a piston skirt at points intermediate the usual pin bosses, and lobes carried by and extending from said resilient body, said lobes being perforated to permit the passage of a piston pin therethrough.

40 12. A piston skirt expander comprising a resilient element having arcuate skirt-engaging portions, and a pair of opposed lobes extending from said resilient element intermediate said arcuate skirt-engaging portions, said lobes being perforated to permit the passage of a piston pin therethrough.

45 13. A piston skirt expander adapted for use with an expandible and contractible piston skirt carrying connecting rod supporting means including bosses, which comprises a spring metal member adapted to extend crosswise of the connecting rod supporting means with its opposite ends adapted to engage against opposite sides of the skirt under tension, and resilient sheet metal lobes intermediate the ends of said member and to one side of the longitudinal median line thereof and adapted to have the connecting rod supporting means project therethrough, and the lobes being also adapted to exert outward pressure against said bosses.

14. An expander for pistons comprising a spring metal member having oppositely disposed spring portions which are of substantially arcuate shape in a transverse plane and which are adapted to engage the opposed walls of an expansible and contractible piston skirt, and a pair of spaced, perforated lobes projecting from said

member intermediate said portions, said lobes being parallel to a median plane intersecting said portions and constructed and arranged for engagement with connecting rod support means for supporting the expander within the piston skirt. 5
